DRIFT RECORDER

Francis W. Lake and John H. Wallace, Jr., Whittier, Calif., assignors, by mesne assignments, to Technical Oil Tool Corporation, Ltd., Los Angeles, Calif., a corporation of California

Application December 21, 1929, Serial No. 415,822

1 Claim. (Cl. 33—205.5)

This invention relates to improvements in the art of surveying bore holes, and more particularly to a method and an apparatus for measuring the degree of deviation of bore holes from vertical.

Generally, the deviation of the bore holes from vertical is made with intricate and costly devices which are lowered into the bore hole either on the end of a cable or on a string of tubing.

10 The prior methods of determining the deviation have several practical disadvantages. In determining the deviation from vertical of the bore hole during drilling, it is necessary to pull the drill pipe if the device is to be lowered on a string of tubing. The delicacy of the devices previously suggested requires careful handling and frequent and costly repairs.

20 An object of the present invention is to eliminate the above mentioned disadvantages and to provide a quick and effective method of and means for determining the deviation from the vertical of the bottom of the bore hole in drilling.

25 Another object of the invention is to provide a simple and sturdy device to accomplish the above purpose.

30 The invention resides in the use of a device for determining the deviation of the lower portion of a bore hole from vertical at successive stages during the drilling of a well for the purpose of correcting for any deviation. It is more essential to drill a straight hole than to survey an already existing crooked one.

35 The invention also resides in lowering an inclination recording device into a bore hole by freely introducing it into the drill pipe with the drilling mud being circulated therethrough.

40 Generally the device consists of a record producing device whereby the inclination of the bore hole is recorded and a weighted means adapted to move to the plane of maximum inclination said inclination being then recorded by the recording device.

45 The invention further resides in an inclination recording device comprising a cylindrical housing containing a freely pivoted carrier weighted on one side to move into the plane of maximum inclination, a weighted wheel pivoted on the carrier to rotate in said plane of maximum inclination, an inclination indicating means being provided on the wheel, and a record receiving piston above said wheel to be moved into engagement with the wheel to produce a record.

50 The invention still further resides in the provision of a recoil or shock-absorbing means at or

near the bottom of the drill pipe to receive the device dropped into the drill pipe and to hold said device parallel to the axis of said drill pipe so that the deviation as recorded by the device will be the deviation of that portion of the bore hole in which the section of the drill pipe containing the recoil or shock absorbing means is located.

55 Referring to the drawing which discloses certain embodiments of the invention by way of illustration:

Fig. 1 is a longitudinal section, partly in elevation, of a device for recording the deviation from the vertical of any desired portion of a drill hole, said deviation recording device being adapted to be dropped freely into the drill pipe during the circulation of the rotary drilling mud;

Fig. 2 is a longitudinal section through the lower portion of the drill pipe, showing the arrangement of the recoil or shock-absorbing means and the deviation determining device in operative or recording position;

Fig. 3 is a transverse section along line 3—3 of Fig. 2;

Fig. 4 is a transverse section along line 4—4 of Fig. 1, and shows a record receiving element in position;

Fig. 5 is a transverse section along line 5—5 of Fig. 1, showing a weighted wheel having in its periphery a deviation indicating means capable of transferring a record to a chart thereto;

Fig. 6 is a diagrammatic longitudinal view of a bore hole showing a drill pipe with the drill bit therein, a portion of said drill pipe being removed to show the location of the deviation recording device in place;

Fig. 7 is a longitudinal view, partly in section, of a modified form of construction of the lower portion of the deviation recording device.

As shown in the drawing, and especially in Fig. 40 1, the recording device consists of a cylindrical housing 1 with a cone-shaped bottom shoe 2 attached to its lower end and a closure head 3 attached to its upper end. The deviation recording means is contained in the cylinder 1, and 45 comprises a freely turning spindle 4 which rotates in bearings 5 and 6, the latter being held by means of a bushing 7 so that the spindle 4 rotates in the longitudinal axis of the device. Said spindle 4 is flared at the top 8, and has a carrier plate 9 and 50 a weight 10 attached thereto. A wheel 11 with recording characters 12, such as type, marked on its periphery is pivotally mounted at 13 on the plate 9, said wheel 11 having an eccentrically attached weight 14. A piston 15 sliding in a sleeve 55

15a is installed in the pipe 1 above the wheel 11 and carrying a record receiving member 16 secured by screws 16a. The piston 15 is actuated by an eccentric 17 to be moved downwardly and to engage with the recording characters 12 on the wheel 11. The eccentric 17 is in its turn actuated by a clock or a similar device 18. The weight 10 rotates the spindle 4 and brings the wheel 11 into the plane of maximum deviation, while the weight 14 on said wheel 11, always being at the lowest point, causes the graduations 12 to register on the record-receiving member 16 the deviation from vertical of that point of the bore hole. The zero point on the wheel 11 is uppermost when the position of the device is vertical. This wheel carries degree marks whereby any deviation from vertical to either side of the axis of the device is recorded.

As shown in Fig. 1, the device 18, for the actuation of the eccentric 17 and of the piston 15, consists of an ordinary clock mechanism 29 operating a minute shaft 31. Said shaft 31 corresponds to the minute shaft of an ordinary clock mechanism. A cam 32 is also mounted on shaft 31. The cam 32 is so mounted that it is manually revolvable in the clockwise direction by revolving shaft 31 as is common in clock mechanisms. A gear 33 is mounted on the axis 30 and is in operative engagement with gear-wheel 36 operated by a tension spring 37. The eccentric 17 is also mounted on the same axis 30. Half of the periphery of the gear 33 is provided with teeth as at 34 and the other half is smooth as at 35. A lever 38, hinged at 39, terminates in a pawl which is in operative engagement with gear 36. A vertical lever 40, fixed at 41 to lever 38, terminates in a hook which co-operates with the shoulder 42 of cam 32.

The device 18 functions as follows: The cam 32 is rotated counter-clockwise the number of minutes required for the device to reach its ultimate position. The clock mechanism is released as the device is introduced into the well. The operation of the clock mechanism causes the cam 32 to rotate in the direction shown by the arrow. Then the cam shoulder 42 raises the lever 40, this automatically raises the lever 38 out of engagement with gear 36, thus permitting spring 37 to rotate said gear. Gear 33 is then rotated by gear 36 in the clockwise direction. Since gear 33 is geared along half of its periphery, it will only rotate about 180°, thus causing the eccentric 17 to move piston 15 into and out of engagement with the recording characters 12 on wheel 11. This will result in but one impression and prevent confusion by the repetition of impressions.

The recoil or shock-absorbing means, as shown in Figs. 2 and 3, are usually placed in the bottom of the lowest section of the drill pipe just above the drill bit, but they may be placed at any other point in said drill pipe, depending upon the location of the point at which it is desired to determine the deviation from vertical. A coil spring 19, of a resilience sufficient to withstand the impact of the device dropped from the top of the bore hole into the drilling mud in the drill pipe, is placed on the shoulder 20 of the tool joint 21 connected to the lower end of the drill pipe 22. A ring 23 with a bevelled inner surface 24 is set on the coil spring 19 and held centrally with respect to the drill pipe 22 by means of a plurality of centering leaf springs 25, the bevelled inner surface 24 of the ring 23 having a pitch which corresponds to that of the cone-shaped bottom shoe 2 of the recording device shown in Fig. 1. Holes 24a are

provided in the body of the ring 23 for a free passage of the drill mud therethrough. A plurality of guide springs 26 attached to the ring 23 direct the recording device into the ring 23 and maintain said device in the longitudinal axis of the drill pipe 22 during the taking of said record of the deviation.

Fig. 7 shows a modified form of a device for recording the deviation of the bore hole from vertical. In this modified form the cone-shaped bottom shoe attached to the lower end of the hollow pipe 1 is substituted by a heavy spring 28. It is obvious that, if this modified form of a device is used, it will be unnecessary to use the separate recoil or shock-absorbing means shown in Fig. 2, since the impact will be absorbed by said spring 28.

The recoil or shock-absorbing means having been assembled and installed in the drill pipe 22 as described hereinabove, said drill pipe is lowered into the bore hole 21 to perform the usual drilling operation. When it is desired to determine the deviation of the bottom of the bore hole from vertical, the deviation recording device, assembled as shown in Fig. 1 and described hereinabove, is dropped into the drill pipe. The drilling liquid, such as rotary mud, is circulated. The device drops, or is allowed to descend with the mud, through the drill pipe until it reaches the recoil or shock-absorbing means, the latter receiving the impact and aligning said device with the longitudinal axis of the drill pipe 22. It is to be understood that the outside diameter of the deviation recording device must be substantially smaller than the inner diameter of the tool joints which connect the individual lengths of the drill pipe 22, so that said device may freely pass through the openings in these tool joints, being guided through them by the cone-shaped bottom end 2. When the deviation recording device reaches the shock-absorbing means, the cone shaped bottom shoe 2 guided by the springs 26 enters into the correspondingly bevelled ring 23, said centering springs 26 aligning the hollow pipe portion 1 of the device with the longitudinal axis of the drill pipe 22. If the bore hole, and therefore the drill pipe 22, is not vertical at the point where the recoil or shock-absorbing means are located, the weight 10 attached to the spindle 4 will move so as to be in the plane of maximum deviation, thereby rotating plate 9 and the pivotally attached wheel 11 into the same plane. At the same time, the wheel 11 rotates on its pivot 13 so that the weight 14 attached to said wheel is at the lowest possible point. The clock 18, being set so as to give the different parts a sufficient period of time to come to rest after reaching the recoil or shock-absorbing means, then actuates the eccentric 17 to cause a downward movement of the piston 15, thus bringing the record producing member 16 into engagement with the type 12 on the wheel 11 opposite said record-producing member 16. This is clearly shown in Figs. 4 and 5, Fig. 5 showing a top view of wheel 11 when the deviation indicating device is in a vertical position, and Fig. 4 showing the record producing element 16 with a number "5" recorded on same by the graduations 12, thus indicating that the deviation indicating device was 5 units from vertical at the time of taking of the record. In the meantime the "freezing" of the bit in the bore hole is prevented by continuing the circulation of the rotary drilling mud.

After a record is produced, the deviation recording device may be removed from the bore

hole by withdrawing the drill pipe, and the record produced by said deviation-recording device gives the inclination of the bore hole from vertical at the respective point. Before withdrawing 5 the drill pipe, the circulation of the drilling mud down through the pipe is necessarily cut off according to the prevailing practice in order to permit the drill pipe sections to be disconnected ("broken off" according to drilling parlance) 10 preparatory to their removal as the drill pipe is gradually elevated section by section.

It is to be understood that the deviation of the bore hole may be determined without the use 15 of a drill pipe and without the circulation of a liquid, such as rotary mud. Such is the case when, for example, the drill pipe string is out of the bore hole for changing the drill bits, said bore being filled with the fluid. The record producing device provided with centering springs or other 20 means may be lowered into the hole and allowed to drop to the bottom. Means, such as a spring 25 attached to the lower end of housing 1 containing the deviation indicating device (Fig. 7), are then provided to absorb the shock when said

device reaches the bottom of the hole. After a predetermined period of time, during which the parts of the device are permitted to come to rest and a record is automatically taken, the record producing device may be withdrawn from the bore hole by some known means, such as for example a fishing tool. 5

It is also to be understood that the specific disclosures herein made are merely illustrative of the generic invention and are not to be considered as limiting, since many variations may be made within the scope of the claim hereof by those skilled in the art. 10

We claim:

In a cushioning and positioning device for a 15 record taking instrument, a coil spring adapted to be placed in a drill pipe string, a ring placed on said coil spring, centering springs for said ring, and a plurality of guide springs adapted to receive the record taking instrument and to maintain the same in the longitudinal axis of said drill pipe string. 20
